2,524,836

PERMANENT MAGNET ELECTRODYNAMIC
LOUD-SPEAKEREarl L. Russell, Cleveland, Ohio, assignor to The
Rola Company, Inc., Cleveland, Ohio, a corpora-
tion of Ohio

Application April 2, 1947, Serial No. 738,894

5 Claims. (Cl. 179—115.5)

1

This invention relates to loud speakers, and particularly to loud speakers of the permanent magnet type.

Loud speakers utilizing a permanent magnet for the field structure are subject to the accumulation of foreign particles in the confined space between the voice coil forms and the opening therefor in the front plate of the magnetic structure. Great care must be exercised in the manufacture of the loud speaker to avoid the possibility of magnetic particles being attracted to and held by the magnetic structure, as otherwise their presence would interfere with the normal reciprocating movement of the voice coil within the air gap and cause a scratching noise in the reproduction. The centering of the voice coil form within the air gap is also important. The construction utilized, however, must be sufficient not only to maintain the proper spacing between the component parts, but must enable the speaker to withstand rough handling incident to the packing and shipment of the loud speakers from the manufacturer to the set manufacturer, and then to the ultimate user.

An effort heretofore has been made to overcome the aforementioned difficulty by permanently fastening the cone and housing assembly to the field assembly after the voice coil form has been centered by means of a gauge with respect to the pole tip of the magnetic structure. The difficulty with such arrangement, however, has been that if any magnetic particles should be entrapped between the voice coil form and the pole tip, or if the voice coil is not centered exactly, it has been necessary to destroy the diaphragm, the spider or centering member, the voice coil and the form in order to get at the space in the region of the air gap for the purpose of freeing the gap of foreign particles or in order to re-center the voice coil. In loud speakers utilizing a permanent magnet, such occurrence is apt to be sufficiently frequent to constitute a major item in the servicing and repairing of loud speakers.

An object of the present invention is to provide a loud speaker wherein the cone or diaphragm and its associated housing assembly can be removed from the field assembly without destroying or disturbing the relationship of the parts forming the diaphragm assembly, thereby enabling the field structure, in the region of the air gap, to be effectively cleaned or centered and the parts re-assembled in an expeditious manner.

Referring now to the drawings, Fig. 1 is a side elevation of a loud speaker embodying the present invention; Fig. 2 is an exploded view in side elevation of the assembly shown in Fig. 1; Fig. 3 is

2

an end view of the field structure as viewed in the direction indicated by the arrows 3—3 in Fig. 2; Fig. 4 is a rear view of the assembled loud speaker with a portion thereof broken away; Fig. 5 is a section taken on a plane indicated by the line 5—5 in Fig. 4, and Fig. 6 is a section taken on a plane indicated by the line 6—6 in Fig. 4.

The loud speaker with which the present invention is shown has a permanent magnetic field 10 which includes a shell type core, indicated in general at 10, and preferably comprises a strip of metal that is bent to form an open frame having a front plate 11, a back plate 12, a top plate 13 and a bottom plate 14. The front plate has an opening 15 therein and the back plate has a pole piece 16 extending into the shell and substantially parallel to the top and bottom plates thereof. The pole piece terminates in a pole tip 17 which is concentrically disposed within the opening 15 and cooperates therewith to provide the air gap in which the voice coil is adapted to operate in the usual way. The pole piece 16 is held within central position within the shell by means of a resilient cup-shaped member 26 that is soldered or otherwise securely fixed to the back of the front plate and is adapted to engage a tapered surface 21 on the pole piece to exert tension thereagainst, so as to hold it firmly in central position with respect to the shell.

The loud speaker of the present invention includes a diaphragm 25 preferably in the form of a cone to the throat of which a voice coil form 26 is attached. The form carries the usual voice coil 27 and is held in centered position by a spider or centering member 30 which extends from the neck of the diaphragm to the space 31 of the cone housing 32. The periphery of the cone is fastened, as by cement and gasket 33, to the periphery of the housing.

The field structure is attached to the cone assembly by fastening members 35 which extend through openings 36 in a plate 37 and are in threaded engagement with registering openings in the base of the cone housing. As is shown in Fig. 2, the openings 36 are larger than the diameter of the threaded shank of the fastener 35, as a result of which adjustment may be made between the field structure and the cone assembly whenever the screws are loosened.

The foregoing describes the component parts of the loud speaker, the assembly of which may be made in accordance with that disclosed and described in my copending application Serial No. 127,961, filed November 17, 1949, and assigned to The Rola Company, Inc. Briefly in carrying out

the method of assembly, the plate 37 is staked or otherwise securely fastened to the front plate 11, as by bosses 40 which are extruded from the front plate and are adapted to enter correspondingly shaped openings in the plate 37. Additionally, the attachment is made by threaded fastening members 41, as is shown in Fig. 3. The plate and shell as a unit are then fastened to the cone housing 32 by means of the securing members 35, these being accessible from the rear of the housing as is shown in Fig. 4, inasmuch as the plate 37 is wider than the material of which the shell 10 is made.

After the shell has been assembled to the housing, then the pole piece 16 is centrally located therein by means of a suitable gauge placed between the pole tip and the wall of the opening 15, and is locked in place by the resilient centering member 20, after which solder is applied to hold the pole piece to the back wall of the shell and to hold the centering member to the front plate of the shell.

After the assembly of the magnetic structure, the centering member 20 is cemented at its outer periphery to the base 31 of the cone housing, while being centered with respect to the axis of the pole tip by means of a gauge that is inserted within the air gap. The assembly of the cone and its associated voice coil form to the centering member 20 is made by applying cement to the neck of the cone on the outer portion thereof and then inserting the voice coil form into the air gap, using a customary centering gauge to space it with respect to the pole piece. The form is inserted until the centering member fits snugly against the neck of a cone, whereupon the cement operates effectively to join the two parts together. While the centering gauge is still in position, the base of the cone is cemented to the cone housing and sealed by means of the gasket 33 which is cemented thereto.

In the event of the voice coil form being inaccurately centered with respect to the pole piece, then it is only necessary to loosen the screws 35 and move the field assembly with respect to the cone assembly, using the customary centering gauge between the voice coil form and the pole tip, and then tightening the members 35.

In the event of metallic particles or other foreign particles being entrapped between the pole tip and the voice coil form, then upon removal of the fastening members 35, the field structure may be removed as a unit from the cone assembly, the air gap may be thoroughly cleaned and the parts reassembled by means of a centering gauge and replacement of the screws 35.

Heretofore it has been necessary to destroy the cone, together with its associated centering member, voice coil and voice coil form in order to relocate a form with respect to the walls of the air gap, or to make the air gap accessible for cleaning purposes. An advantage of the present invention, however, is that the adjustment and cleaning can be made without destroying any of the component parts, and without disturbing the connection between the cone, the centering member and the housing. Thus, a saving is made in parts and considerable reduction is effected in the time required to rebuild the loud speaker. Moreover, the invention is advantageous in that the cone assembly and field structure may be quickly adjusted merely by the insertion of a centering gauge between the voice coil form and the pole tip at the time of tightening of the fastening members, which are readily accessible from the exterior part of the unit.

I claim:

1. A loud speaker having a diaphragm, a voice coil form attached thereto, a centering member extending from the form radially thereof, a housing for the diaphragm, means for attaching the outer portion of the diaphragm to the housing, a field structure embodying a permanent magnet and including a shell-type core having an opening for receiving the voice coil form, a pole piece disposed within said shell type core, a centering member secured within said shell type core and adapted to fixedly enclose the tip of said pole piece, thereby securing it firmly in central position with respect to said shell, a plate rigidly attached to the core and removable loose fitting fastening means for connecting the plate to the housing.

2. A loud speaker having a diaphragm, a voice coil form attached thereto, a centering member extending from the form radially thereon, a housing for the diaphragm, means for attaching the outer portion of the diaphragm to the housing, a field structure including a permanent magnetic type core having an opening for receiving a voice coil form, said core embodying an open frame of uniform width, a pole piece disposed within said core frame, a resilient centering member secured within said core frame and adapted to fixedly enclose the tip of said pole piece thereby retaining it firmly in central position with respect to said core frame, a plate rigidly attached to the frame and being wider than the frame, and loose fitting fastening means for detachably connecting the plate to the housing, said means being accessible from the exterior of said field structure.

3. A loud speaker having a permanent magnetic field structure including a core having a front plate with an opening therein, and a back plate, a pole piece extending from the back plate and having a pole tip disposed within said opening and disposed concentrically with respect thereto, a centering member secured to the front plate within said core structure and adapted to fixedly enclose said pole tip thereby retaining it firmly in central position with respect to said core structure, a diaphragm having a voice coil and a centering member attached thereto, the form being positioned between the pole tip and the wall of said opening, a housing, means for rigidly connecting the centering member and the diaphragm to the housing, a member rigidly fastened to the front plate and disposed between it and the housing and having an opening in registration with that in the front plate through which the voice coil form extends, said member having spaced openings therein, and said housing having openings in registration with the last-named openings, threaded fastening members extending through said last-mentioned registering openings for securing the magnetic field structure to the housing, the openings in the member being larger than the cross-sectional area of the associated fastening members, whereby the member and field structure as a unit may be adjusted radially with respect to the voice coil form.

4. A loud speaker having one unit comprising a permanent magnetic field structure, including a core, a pole piece, a resilient centering member secured within said field structure and adapted to fixedly enclose the tip of said pole piece thereby firmly retaining it in central position with respect to said field structure, and a plate connected together as a unit, and another unit comprising a diaphragm, a voice coil form, a center-

ing member and a housing connected together as a unit, and means for detachably connecting the units, said means including a loose fitting connection by means of which one unit may be radially shifted with respect to the other unit for centering the voice coil form within the air gap, said means including threaded fastening members which may be tightened after radial adjustment has been made between the magnetic structure and the housing, and which are accessible from the exterior of the magnetic structure.

5. A loud speaker having a conical diaphragm, a voice coil form attached thereto, a flaring housing about the diaphragm, means for attaching the outer portion of the diaphragm to the outer portion of the housing, a centering member for the voice coil form extending radially outward therefrom and attached to the inner portion of the housing, a field structure of the shell type having a front with an opening for receiving the voice coil form, a pole piece disposed within said field structure, a resilient centering member secured within said field structure and adapted to fixedly enclose the tip of said pole piece thereby firmly retaining it in central position with respect to said field structure, a plate resting against said front and rigidly attached thereto and overhanging opposite sides of the field structure, and

loose fitting fastening means at the overhanging portions of said plate for detachably connecting the plate to the inner portion of the housing, said means being accessible from the exterior of said field structure.
